UNITED STATES PATENT OFFICE.

WILLIAM R. KINNEAR, OF COLUMBUS, OHIO.

DESIGN FOR A CEILING-PANEL.

SPECIFICATION forming part of Design No. 25,925, dated August 11, 1896.

Application filed July 3, 1896. Serial No. 598,046. Term of patent 7 years.

To all whom it may concern:

Be it known that I, WILLIAM R. KINNEAR, a citizen of the United States, residing at Columbus, in the county of Franklin and State 5 of Ohio, have invented and produced a new and original Design for Panels for Ceilings, Walls, &c.; and I do hereby declare the following to be a full, clear, and exact description of the same, reference being had to the accompanying drawing, forming a part thereof.

The panel, as shown in the accompanying drawing, is substantially square in its general contour, and around its edges is a line of spindle-work 1. Located on one side is a 15 series of staple-shaped bars 2, having their ends curled inward. The staple-shaped figures are arranged parallel to each other, and between them are straight bars 3, having beads opposite their ends. Between the staple-shaped figures and the spindle-work on the adjacent edge is a series of convolutes 4 and spear-shaped figures 5, the convolutes and spear-shaped figures occurring alternately. The ornamentation thus far de-

scribed occupies about one-half the surface 25 of the panel. Arranged parallel to the spindle-work of the opposite edge of the panel are bars 6, which have small volutes near the center of the side and are prolonged at their outer ends into scrolls bearing the one a leaf 30 7 and the other a rosette or conventional flower 8. The two rosettes or flowers 8 are connected by a curved beaded line 9, which is ornamented at its middle with a small figure 10. Opposite the center of this side is also a bell-shaped figure 11, from which extend curved beaded lines 12, terminating in half-rosettes 13 at opposite sides of the panel.

What I claim, and desire to secure by Letters Patent, is—

The design for a ceiling-panel, substantially as herein shown and described.

In testimony whereof I affix my signature in presence of two witnesses.

WILLIAM R. KINNEAR.
